(57) **CLAIM**

The ornamental design for a cleaner for dust canister, as shown and described.

DESCRIPTION

FIG. 1 is a front perspective view of a first embodiment of a cleaner for dust canister, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a cross-sectional view thereof, taken in the direction of line 8-8 in FIG. 2;

FIG. 9 is a front perspective view of a second embodiment of the cleaner for dust canister, showing our new design;

FIG. 10 is a front view thereof;

FIG. 11 is a rear view thereof;

FIG. 12 is a left-side view thereof;

FIG. 13 is a right-side view thereof;

FIG. 14 is a top view thereof;

FIG. 15 is a bottom view thereof;

FIG. 16 is a cross-sectional view thereof, taken in the direction of line 16-16 in FIG. 10; and,

FIG. 17 is another perspective view of the cleaner for dust canister shown in an environment of use.

The broken lines illustrating portions of the cleaner for dust canister form no part of the claimed design. The additional broken lines in FIG. 17 show environmental structure that forms no part of the claimed design.

1 Claim, 17 Drawing Sheets
